(57) **CLAIM**

The ornamental design for a cross strut, as shown and described.

DESCRIPTION

FIG. 1 is a perspective view of a cross strut showing my new design; and,

FIG. 2 is a front view thereof, the rear view being a mirror image thereof.

The cross strut is shown with a symbolic break in its length. The appearance of any portion of the cross strut between the break lines forms no part of the claimed design.

1 Claim, 2 Drawing Sheets

FIG. 1

FIG. 2
